UNITED STATES PATENT OFFICE.

WILLIAM J. RUFF, OF QUINCY, ILLINOIS.

CARBURETER.

1,349,006.

Specification of Letters Patent. Patented Aug. 10, 1920.

Application filed September 18, 1916. Serial No. 120,633.

To all whom it may concern:

Be it known that I, WILLIAM J. RUFF, a citizen of the United States, residing at Quincy, in the county of Adams and State 5 of Illinois, have invented certain new and useful Improvements in Carbureters, of which the following is a specification.

This invention relates generally to carbureters, but is more particularly designed 10 and intended for use with carbureters for kerosene or for other fluids less volatile than gasolene or naphtha. The principal object of the invention is to provide a new and improved construction, combination and arrangement of parts for forming an explosive mixture with a liquid fuel and air.

In the accompanying drawings, Figure 1 is a view partly in section, of a carbureter 20 constructed in accordance with the principles of my invention; Fig. 2 is another sectional view of the carbureter; Fig. 3 is a plan section taken on the line 3—3 of Fig. 1; and Fig. 4 is a section of the vaporizer.

The heavier the fuel oil, the less readily 25 it will evaporate, but will remain in a wet state and instead of being held in suspension as is necessary for successful carburetion it will condense unless special means is provided for evaporating the oil in a 30 higher temperature, which will remove it from the so-called wet state into the suspension vapor state. Air saturated with a liquid, as it passes the spray nozzle of a carbureter, precipitates some of that liquid 35 in the form of drops as soon as it is rarefied, which means that air entering an engine and saturated at the nozzle deposits some of the fuel in the manifold while still more is drawn into the cylinder itself. In the case 40 of kerosene, drops are formed which are larger than gasolene drops, because they have no surface tension, and are harder to vaporize.

The conditions existing with a wide open 45 throttle are greatly different from those with a partially open throttle; with a restricted passage of air it follows that the air is capable of picking up or vaporizing less kerosene from the nozzle, and besides 50 the air being rarefied by the partial vacuum created by the engine, the rarefaction tends to throw down the liquid into drops. To hold any liquid in gaseous suspension at a lower pressure, the air entering should be 55 hotter or above the normal temperature, to operate the engine with a partially closed

throttle, the pressure under those conditions being lowered and less instead of more heat being available for revaporizing such fuel as does condense.

A combustible mixture is formed by gasolene vapor and air in any proportion between 1 per cent. and 5 per cent. of gasolene while vaporized kerosene has only one-half that latitude in per cent. In order, therefore, to design a carbureter for kerosene it must be twice as accurate as a gasolene carbureter and is really in effect a vaporizer. The most satisfactory basis for working out kerosene carburetion is to pass about 20 per 60 cent. of air through the vaporizer and then to mix this with the remaining 80 per cent. of air immediately before the charge passes into the cylinder, the effect being about the same as the direct admixture of a volatile 65 spirit and air. The present invention overcomes the difficulties above mentioned by the construction which will now be set forth.

This carbureter comprises a housing 1 having an air admission port 2 and an air passage 3 divided to form an upper admission port with a valve seat 4 and a lower admission port with a valve seat 5. Between these ports and valve seats 4 and 5 70 are inserted in the wall of the casing between which a threaded adjusting member 8 is movable. Within this adjusting member 8 a valve stem 9 is threaded so that the adjusting of 75 the member 8 will move the valve stem up or down depending upon the direction of rotation of the member. At the upper end of the stem is a valve 10 to coöperate with the valve seat 4 and at the lower end of the 80 valve stem is a smaller valve 11 to coöperate with the seat 5. The stem is of such a length that when one valve is on its seat the other valve is raised from its seat. The adjusting member 8 is slidable between 85 glands 6 and 7 and interposed between it and a valve guide 12 adjacent each valve seat is a spring 13 by which the valves are held in position.

Connected below the lower valve 11 is a 90 casing 14 to which a cylindrical housing 15 is attached containing a porous member 16 which is hollow or cylindrical in form and is held in place by a plate 17 at the outer end through which a fastening rod 18 extends threaded into a spider 19 at the other 95 end of the cylindrical casing 15 so that the 100

air which passes through the lower valve 11 also passes freely to the interior of the porous member 16.

Extending laterally from the casing 15, as shown more clearly in Fig. 2, is a tubular connection 20 to which a fuel admission housing 21 is connected. This housing has a float 22 therein with a valve 23 at the bottom for admitting liquid fuel through a fitting 24 in accordance with the desired level determined by the position of the float 22 and shown by the fuel level in this figure which is just sufficient to cover or partially submerge the lower side of the member 16 in the casing 15.

Extending upwardly from the top of casing 15 is a member 25 which forms a cylindrical valve seat 26 for a hollow valve 27 and also a portion of a mixing chamber 28 communicating therewith. This valve has a narrow slot or opening 29 and two wider openings 30 all of which are spaced so that when the slot 29 is in communication with the chamber 28, and centrally located, the lower edges of the openings 30 are in communication with the interior and top of the casing 15. At the bottom of the chamber 28 communicating with the valve seat 26 are holes 31 by means of which any fluid which is condensed in the chamber 28 will flow back through the holes 31 into the valve seat 26 and may then return to the casing 15. In the circular wall of the chamber 28 are a plurality of inlet passages 32, clearly shown in Figs. 1 and 3, all of which communicate on the outside of the chamber with a passage or jacket 33 which is connected with a chamber 34 on the outer side of the valve 10 so that the air passing through the valve 10 will enter the chamber 28 through the inlet passages 32 with a whirling motion which tends to throw any condensation from the walls of the casing and to revaporize it.

A cover plate 35 extends over the top of chamber 28, jacket 33 and over the top of valve 10 forming the chamber 34. In this portion of the cover plate above the valve 10 is an adjusting screw 36 to limit the opening movement of the valve 10. Extending through the cover plate and downwardly into the chamber 28 is a cylindrical member 37 which has a connecting flange 38 at its outer end for attaching the carburetor 55 to a manifold or to a cylinder. This cylindrical portion 37 forms a sort of a separator to assist in insuring that the mixture which escapes therefrom contains vaporized fuel.

At one end of the valve 27, as shown in Fig. 2, is an arm 39 by means of which the valve may be adjusted in position opening more or less of a port between the casing 15 and the mixing chamber 28. In any position there will be some opening through the valve, and the adjusting screw 36 may also

be set so that there will be some opening between the lower valve 11 and its seat.

In operation the air entering the inlet 2 is usually heated by proximity to the discharge manifold, by water jacket or such well known means, and this heated air passes through both of the valves 10 and 11 when the carburetor is in normal operation. The lower or smaller valve 11 may be designated the vaporizer valve and the upper or larger valve is the air auxiliary valve. In normal operation after the engine is started the adjustment of the member 8 and the strength of the springs 13 is such that the vaporizer valve will allow about 20 per cent. of the air to circulate through the vaporizer section while the remaining 80 per cent. passes through the valve 10 after vaporization of the fuel has taken place with this vapor in a heated condition just prior to its entry into the intake manifold. In starting, the adjustment may be such that only the vaporizer valve 11 is open, as shown by Fig. 2, in which position all of the air will pass through the vaporizer making a rich mixture which is advantageous in starting. The regulation of the passage and division of the air and attemperating the same is all done automatically and requires no attention after the apparatus is set and adjusted, so that it makes no difference if the engine to which the carburetor is applied is working under a heavy load and requires the richest possible mixture or whether it is operating under a light or moderate load requiring a lean mixture. The device adjusts itself automatically to every condition without the aid of an operator; in fact the device would automatically act along before the operator is aware that a change in the position of the mixture, the amount of hot or cold air, or the throttling of the same is necessary, for a satisfactory and economical regulation of the fuel and engine requirements.

It is also contemplated that the vaporizing member 16 may be provided with a heating coil 39, as shown by Fig. 4, which is connected to the terminals of a battery 40. The coil may be energized continuously, or only when desired, as in starting. It should be understood, furthermore, that this vaporizing member 16 may be composed of any pervious material, such as felt or a screen, as well as porous material.

What I claim is:

1. A carburetor comprising a housing having a mixing chamber and a divided air passage leading to the mixing chamber; a valve in each division of the air passage; a valve stem common to both valves; variable spring tensioning means for said valves for automatically controlling the passage of air through the divisions of said air passage; a porous cylinder in one of said divisions; 125

- means for supplying and maintaining fuel at a predetermined height partially immersing the cylinder; and a manually operable valve 5 for controlling the passage of fuel and air from said porous cylinder to the mixing chamber.
2. A carbureter comprising a casing having a mixing chamber and a divided air passage with the divisions of said air passage all connected to the mixing chamber, the connection between one of said divisions of the air passage and the mixing chamber having narrow inlet slots for causing air to swirl around the mixing chamber upon entering the latter; a valve in each of said divisions; a spring-pressed valve stem common to both valves; means for relatively and inversely adjusting the tension on each valve at the same time, one valve closing as the other opens; a porous body in one of said divisions in the path of air passing through the latter; means for supplying and maintaining fuel at a predetermined height partially immersing the body; and a manually operable valve for controlling the passage of air from said porous body to the mixing chamber.
3. A carbureter comprising a housing having a mixing chamber and a divided air passage leading to the mixing chamber with a vaporizing chamber in one of the divisions of said air passage; a valve in each of said divisions; a spring-pressed valve stem common to said valves; means for relatively and inversely adjusting the tension on each valve
- at the same time; a porous body in said vaporizing chamber in the path of air passing through the latter; means for supplying fuel to said vaporizing chamber in contact with said porous body; and a manually operable valve for controlling the passage of air and fuel from said porous body into said mixing chamber.
4. A carbureter comprising a casing having a mixing chamber with a divided air passage connected with the mixing chamber and a vaporizing chamber in one of the divisions of said air passage; a valve in each division of said air passage; a valve stem common to said valves; means for relatively and inversely adjusting the tension of each valve at the same time, one valve closing as the other opens; a horizontally disposed porous cylinder in the vaporizing chamber; means for supplying and maintaining fuel in the vaporizing chamber partially immersing the cylinder, said cylinder being arranged to receive air in an open end and mix such air with fuel as it passes through the body of said cylinder; a valve for controlling the flow of air from said vaporizing chamber to said mixing chamber; and an outlet from the mixing chamber comprising a central tube extending from above below the top of the opening of one of the divisions of the air passage into said mixing chamber.

In testimony whereof I have signed my name to this specification, on this 31st day of August, A. D. 1916.

WILLIAM J. RUFF.
